UNITED STATES PATENT OFFICE.

CHARLES C. BLACKMORE, OF DAYTON, OHIO.

LOCK FOR AUTOMOBILES AND THE LIKE.

Application filed August 25, 1919, Serial No. 319,578. Renewed September 1, 1922. Serial No. 585,832.

To all whom it may concern:

Be it known that I, CHARLES C. BLACKMORE, a citizen of the United States, residing at Dayton, in the county of Montgomery and 5 State of Ohio, have invented certain new and useful Improvements in Locks for Automobiles and the like, of which the following is a specification, reference being had therein to the accompanying drawing.

10 This invention relates to door locks for automobiles and the like. Many of the better makes of automobiles are provided with rods which may be detachably secured to the door to support the storm curtain on the 15 door so that it will swing with the latter as the door is opened and closed. Difficulty has been experienced in attaching the rods to the door in a strong and durable manner, so that they will be held firmly in position 20 when subjected to severe strains. This difficulty is increased by the fact that the expense of installation must be kept very low, and where it is necessary to use additional parts the cost of installing these parts must 25 be taken into consideration as well as the cost of the parts themselves.

The object of the invention is, therefore, to provide the door lock itself with means for supporting the curtain rod; and to provide means of this kind which will be of a 30 strong and durable character.

It is also an object of the invention to provide such a lock with means to yieldably support the curtain rod so that the edge of 35 the curtain will be held firmly in contact with the edge of the adjacent curtain.

Other objects of the invention will appear as the device is described in detail.

In the accompanying drawings, Fig. 1 is 40 a perspective view, partly broken away, of a portion of the side wall of an automobile, showing the invention applied thereto; Fig. 2 is a sectional view taken on the line 2—2 of Fig. 1; Fig. 3 is a perspective view, 45 showing a modified form of socket; Fig. 4 is a perspective view showing a further modification of the socket; Fig. 5 is a perspective view, partly broken away, and showing a yieldable attaching device; Fig. 6 is a plan view of the door with the attaching device shown in Fig. 5; Fig. 7 is a sectional view of the socket of the device of Fig. 5; Fig. 8 is a sectional view taken on the line 8—8 of Fig. 5; Fig. 9 is a sectional view showing 50 a modified form of yieldable attaching de-

vice; Fig. 10 is a plan view of the device of Fig. 9; and Fig. 11 is a transverse sectional view of the device shown in Fig. 9.

In these drawings I have shown several embodiments of the invention for the purpose of illustrating the same, but it will be understood that these embodiments have been shown for the purpose of illustration only and that the invention may take various forms other than those here shown. 60

In Figs. 1 to 4, inclusive, I have shown a lock having means for rigidly supporting the curtain rod, but which will permit the rod to be readily placed in position on, or removed from, the door. In Fig. 1 I have 65 shown a portion of the side wall of an automobile having the usual door 10, which is provided with a lock or latch 11 for retaining the same in its closed position. Secured to the door is a storm curtain 12 and that 70 edge of the curtain adjacent to the free edge of the door is secured to a rod detachably mounted on the door and adapted to support the curtain in such a manner that it will 75 swing with the door and, when the door is 80 in its closed position, will overlap the edge of the curtain 13, which is secured to the fixed part of the side wall. The curtain rod preferably comprises a shank 14 adapted to be inserted in a socket carried by the 85 door and this shank is connected by means of a laterally offset portion 15 with a main portion 16 of the rod which extends upwardly therefrom and to which the edge of 90 the curtain is attached. The laterally offset portion 15 of the rod projects beyond the edge of the door so that when the door is 95 closed the edge of the door curtain will overlap the edge of the fixed curtain. While in ordinary use this curtain rod is not necessarily subjected to severe strains, it frequently happens that it is subjected to severe strains which tend to rotate the shank, as when the rod is used as 100 handle by a person entering, or leaving the car, or for the purpose of opening and closing the door. It has been found in practice that these strains will frequently loosen or distort the socket so that the rod will not be held firmly in its correct position. 105 In order to provide an attaching device which will hold the rod firmly in place and which may be applied to the door at a very small cost, I prefer to mount the socket, 110 either in part or in whole, on one of the fix-

tures on the door, so that it can be secured to the door in its proper position simultaneously with the mounting of the fixture on the door and with little or no additional labor. The door lock is mounted on the door just below the point at which the curtain rod is mounted and for this reason lends itself readily to my purpose and I have in the present drawings shown a part of the lock mechanism as carrying a socket to receive the end of the curtain rod. The socket may be provided in various ways; but I have found that a very strong and durable socket may be provided at a low cost by extending the back wall 17 of the lock casing 11 upwardly and forming the socket therein. As shown in Figs. 1 and 2 this back wall is extended a short distance above the top wall of the lock casing and then bent laterally to form a flange 18 which is provided with a suitable socket. As shown in these figures, the socket consists merely of a non-circular opening formed in the flange 18 and adapted to receive the end portion of the shank 14 of the curtain rod, which end portion is shaped to fit within the non-circular opening, so that the rod will be held against turning movement. The door is provided, in its upper edge, or top rail, with an opening 19 through which the shank 14 of the rod extends, and where the socket consists merely of an opening in the flange, I prefer to provide an additional socket member to support the upper portion of the shank and hold the same in proper alinement with the opening. As here shown, this second socket member consists of a sleeve 20 which extends through the opening and is provided at its upper edge with a flange 21, which engages the top rail of the door to support the sleeve thereon and which also serves as an ornamental finish for the outer end of the socket. This sleeve may extend into the door a suitable distance and serves to guide the shank 14 into the opening in the flange 18 and to hold the same vertically in said opening. If desired, the lower end of the shank may be permitted to project beyond the flange 18 and into engagement with the top wall of the lock casing, which will limit its longitudinal movement. Inasmuch as the flange 18 is rigidly secured to the lock casing, either by forming the same in one piece therewith or by attaching the same thereto, it will be obvious that when the lock casing is mounted in the door the socket member will be placed in position without further effort on the part of the person who is installing the lock. It is then only necessary to form the opening in the top rail of the door and insert the upper socket member therein. As a result of this construction the attaching device can be very quickly and easily applied to the door, and as the parts themselves are of an inexpensive character

the cost of installation is very small. Further, the non-circular opening in the flange forms a very strong and durable attaching device which will not be easily broken or distorted when the rod is subjected to severe strains. 70

In Fig. 3 of the drawings I have shown the lock casing as provided with a socket of a slightly different character. In this instance the rear wall of the lock casing is extended some distance beyond the casing proper and is bent upon itself to form an elongated socket or sleeve, as shown at 22. This elongated socket may, if desired, be non-circular in cross section and the shank 80 of the curtain rod fits snugly within the same. The sleeve may, if desired, extend well up to the top rail of the door and it is unnecessary to provide the upper socket member or sleeve. In this case all that is required is to form the opening in the top rail in alinement with the socket 22 and to provide the same with the usual finishing ring 23. By forming the socket 22 on the wall of the lock casing when the latter is 90 built this attaching device can be produced at a very low cost, and inasmuch as it is installed by the mere act of mounting the lock casing on the door, the cost of installation can be kept at a very low figure. 95

The attaching devices shown in Figs. 1, 2 and 3 are intended to be built into the door of the automobile when the latter is constructed. It frequently happens, however, that it is desired to provide a door with a 100 suitable socket for a curtain rod after the door has been completed and the automobile is in use. Under these circumstances it is preferable that the socket should be mounted on the inner wall of the door. It is difficult, however, to mount the socket in its proper position on the door without interfering with the slide plate in which lock operating lever moves. The available space is so limited that when the socket is placed 110 in position, either the socket itself or the curtain rod will either interfere with the movement of the lock operating lever or will lie so close to the handle of that lever that it is difficult to grasp the handle. To overcome this difficulty I have, in Fig. 4, shown the socket 24 formed integral with the slide plate 25 of the lock. Not only does this construction provide a very strong and durable socket which can be attached to the 120 door with but little effort, but it also insures the proper positioning of the socket with relation to the slide plate. 115

The attaching devices above described are designed to hold the curtain rod in fixed relation to the door and to prevent all turning movement of that rod. By making the attaching device yieldable the curtain rod may be permitted to accommodate itself to the position of the fixed curtain and to hold the 130

- edge of the door curtain firmly in engagement with the fixed curtain at all times, thus insuring a tight joint between the two curtains. To accomplish this the socket may be 5 rotatably mounted and may be acted upon by a spring which will tend to move the socket in a direction to press the curtain rod against the fixed curtain. It is just as essential, however, that the yieldable attaching device 10 should be firmly mounted and should be of such a character that it can be installed at a low cost, as it is that the non-yieldable socket should have these characteristics. As shown in Figs. 5, 6, 7 and 8 the socket comprises 15 a plate 26 rotatably mounted in an opening formed on a part of the lock structure, such for example as the flange 18. This socket plate is provided with a non-circular opening to receive the end of the shank of the curtain rod, and the upper rail 20 of the door is provided with an opening in alinement with the socket. The socket plate, in the form here shown, is provided with a projection, or nose, 27 which is acted upon by 25 a flat spring 28, which tends to rotate the socket in the proper direction, a stop 29 being provided to limit the movement of the socket by the spring. The spring is here shown as mounted on lugs 30 and 31, 30 and the free end of the spring is so arranged with relation to the lug 30 that it will be moved into engagement therewith when excessive movement is imparted to the rod, thus limiting the movement of the socket 35 in a reverse direction and preventing the nose 27 thereon from passing beyond the spring, or the spring being broken when the rod is subjected to excessive strains.
- In Figs. 9, 10 and 11 I have shown another form of yieldable attaching device, in 40 which the socket is in the form of a sleeve 32 having its upper end rotatably seated in the top rail of the door and its lower end rotatably seated in a part of the lock structure, such as the flange 18. This sleeve is non-circular in shape and fits snugly about the shank of the rod, so that it will rotate therewith. A spring 33 is coiled about the sleeve and is connected at one end with the 45 flange 18 as shown at 34, and is connected at its other end with the sleeve or socket 32. In the present instance the sleeve is provided with an arm 35 with which the end of the spring is connected.
- 50 While I have shown and described certain embodiments of my invention, I wish it to be understood that I do not wish to be limited to the details of construction, as various modifications may occur to a person skilled in the art.
- 55 Having now fully described my invention what I claim as new and desire to secure by Letters Patent, is:
1. A lock for an automobile door or the like comprising a socket carried by a part 60 thereof and adapted to receive the end portion of a curtain rod and to hold said rod against turning movement relatively to said socket.
2. A lock for an automobile door or the like comprising a socket formed integral with a part of said lock and adapted to receive the end portion of a curtain rod and to hold said rod against turning movement relatively to said socket. 75
3. A lock for an automobile door or the like, comprising a casing, and a socket member carried by said casing and adapted to receive the end portion of a curtain rod and to hold said rod against turning movement 80 relatively to said socket.
4. A lock for an automobile door or the like, comprising a casing having a portion extending beyond the edge thereof, and a socket member carried by said portion of 85 said casing, and adapted to receive the end portion of a curtain rod and hold the same against turning movement relatively thereto.
5. A lock for an automobile door or the like, comprising a casing having an upwardly extending portion and a flange projecting from said upwardly extending portion, and provided with an opening to receive the end of a curtain rod. 90
6. A lock for an automobile door or the like, comprising a casing having a portion extending beyond the edge thereof and shaped to form a socket to receive the end of a curtain rod. 95
7. A lock for an automobile door or the like, comprising a casing having a portion extending beyond the same and bent upon itself to form a non-circular elongated sleeve to receive the end portion of a curtain rod. 100
8. A lock for an automobile door, or the like, comprising a socket carried by a part of said lock and adapted to receive the end portion of a rod and hold the same against turning movement relatively to said socket, and a part carried by said door and having 110 an opening arranged in alinement with said socket through which said rod may be inserted in said socket. 105
9. A lock for an automobile door, or the like, comprising a casing having a part 115 forming a socket adapted to receive the end portion of a rod and hold the same against turning movement relatively to said socket, and a sleeve mounted in alinement with said socket through which the rod may be inserted in said socket. 120
10. A lock for an automobile door, or the like, comprising a casing having a flange secured thereto, spaced above the same, and provided with an opening to receive the end 125 portion of a rod and hold the same against turning movement relatively to said flange, and a socket member arranged in alinement with said opening, through which the rod may be inserted in said opening. 130

11. A lock for an automobile door, or the like, comprising a socket carried by a part of said lock and adapted to receive the end portion of a rod and hold the same against turning movement relatively to said socket, said socket being yieldable about an axis extending longitudinally of said rod. 65
12. The combination with a curtain rod adapted to be mounted on an automobile door, of a socket adapted to be mounted on said door to receive the end portion of said rod, said socket being yieldable about an axis extending longitudinally of said rod. 70
13. A lock for an automobile door, or the like, comprising a socket rotatably mounted on a part thereof, and a spring acting on said socket to rotate the same. 75
14. A lock for an automobile door or the like, comprising a socket rotatably mounted on a part thereof, a spring acting on said socket to rotate the same, and means for limiting the rotatory movement of said socket. 80
15. A lock for an automobile door or the like, comprising a casing having a flange secured thereto and spaced above the same, a socket member rotatably mounted on said flange, and a spring tending to rotate said socket member. 85
16. A lock for an automobile door or the like, comprising a socket member rotatably mounted on a part thereof adapted to be mounted in alinement with an opening in the door to permit a rod to be inserted through said opening into said socket, and a spring acting on said socket member to rotate the same and said rod. 90
17. A lock for an automobile door or the like, comprising a socket member rotatably mounted on a part thereof adapted to be mounted in alinement with an opening in the door to permit a rod to be inserted through said opening into said socket, a spring acting on said socket member to rotate the same and said rod, and stop devices to positively limit the movement of said socket member and said rod in one direction. 95
18. A lock for an automobile door or the like, comprising a casing having a flange rigidly secured thereto and spaced above the top wall thereof, a socket member rotatably mounted on said flange and having a projection, and a flat spring mounted on said flange and bearing against said projection to rotate said socket member. 100
19. A lock for an automobile door or the like, comprising a casing mounted within the door and having a flange secured thereto and spaced between the top wall of said casing and the top rail of said door, of a socket member rotatably mounted at its ends in said flange and said top rail, and a spring coiled about said socket member and adapted to impart rotatory movement thereto. 105
20. The combination with an automobile door, or the like, having an opening to receive the end portion of an upright curtain rod, of a fixture carried by said door and provided with a socket arranged in line with said opening in the door to support said rod in said opening. 110
21. The combination with an automobile door, or the like, having an opening to receive the lower end portion of an upright curtain rod, of a fixture mounted on said door and having a flange provided with a socket in line with the opening in said door to support said rod in said opening. 115
22. The combination with an automobile door, or the like, having an opening in the upper edge thereof to receive the lower end portion of an upright curtain rod, of a lock casing mounted on said door and comprising a part provided with a socket arranged in line with said opening in the door to support said rod in said opening. 120
23. A lock adapted to be mounted on an automobile door or the like and comprising a part provided with a socket arranged to permit the end portion of a curtain rod to be inserted in said socket. 125
24. A lock adapted to be mounted on an automobile door or the like and comprising a part having a socket formed therein and arranged to permit the end portion of a curtain rod to be inserted in said socket. 130
25. A lock adapted to be mounted on an automobile door or the like and comprising a casing having a portion extending beyond the edge thereof and provided with a socket arranged to permit the end portion of a curtain rod to be inserted in said socket. 135
26. A lock adapted to be mounted on an automobile door or the like and having a part arranged to engage the end portion of a curtain rod and support said rod. 140
27. A lock adapted to be mounted on an automobile door or the like and having a part arranged to receive the end portion of a curtain rod and support said rod in a predetermined position relatively to said lock. 145
28. A lock adapted to be mounted on an automobile door or the like, comprising a casing having an integral part arranged to engage the end portion of said curtain rod and support said rod. 150
29. The combination with an automobile door or the like and a lock for said door, of a curtain rod to be mounted on said door, said lock and said rod having cooperating parts to support said rod. 155

In testimony whereof, I affix my signature hereto.

CHARLES C. BLACKMORE.
